UNITED STATES PATENT OFFICE.

EDWIN E. QUINKER, OF VALDOSTA, GEORGIA.

RETORT.

1,385,470.

Specification of Letters Patent. Patented July 26, 1921.

Application filed May 24, 1920. Serial No. 383,884.

To all whom it may concern:

Be it known that I, EDWIN E. QUINKER, a citizen of the United States, residing at Valdosta, in the county of Lowndes and State 5 of Georgia, have invented certain new and useful Improvements in Retorts, of which the following is a specification, reference being had to the accompanying drawings.

This invention relates to retorts, and particularly to retorts for distilling wood.

The general object of the invention is the provision of a retort so constructed that heat is applied to the sides of the retort as distinguished from the bottom thereof so that 15 the tar, heavy oils and like matters extracted from the wood will not come in direct contact with those plates of the retort which are intensely heated, thus preventing the burning of the tar and other valuable oils.

20 A further object is to provide a construction of this character wherein those side walls of the retort which would ordinarily be subjected to the direct heat of the fire are protected by shield plates supported in such 25 way as to be readily removable and replaceable, thus preventing the burning out of the retort at relatively short intervals and permitting the shield plates, when burned out, 30 to be readily withdrawn and new shield plates put in place without delay.

A further object is to so construct the retort that it will be extremely effective in practice, thoroughly protected so that the heat will be conserved, and in which the heat 35 is directed against the retort in the most effective manner.

Other objects will appear in the course of the following description.

My invention is illustrated in the accompanying drawings, wherein:—

Figure 1 is a side elevation of a retort and furnace used for the dry distillation of wood, the retort and furnace being partly broken away;

Fig. 2 is a section on the line 2—2 of Fig. 1;

Fig. 3 is a perspective view of two of the shield plates;

Fig. 4 is a sectional view on the same lines 50 as Fig. 2 but showing a modified form of retort.

Referring to these drawings, and particularly to Figs. 1 and 2, it will be seen that the retort proper, which is designated 10, is 55 cylindrical in general form. One end of the retort is closed by a door, which is not illus-

trated in detail and which forms the subject matter of a co-pending application executed of even date herewith. The other end of the retort is closed by the brick wall 11 of a furnace. The retort is supported on a brick base 12 and the upper portion of the retort is covered by a layer of brickwork or like material 13 which extends over the top and partly down the sides of the retort. Leading from the furnace is a stack 14, and extending from the bottom of the retort is the tar outlet pipe 15, and extending from the top of the retort is the outlet pipe 16 for the discharge of light vapors. This outlet pipe 16 is adapted to lead to a condensing worm of the usual character, while the tar outlet is adapted to lead to any suitable receptacle into which the tar or heavy matters are discharged.

Extending upward and inward from the lateral margins of the brick base 12 are the arches 17 which are lined internally with fire brick 18. Each arch 17 and its lining brick 18 extends over a furnace space 19, there being one on each side of the retort, from which descends an ash pit 20. Where the upper end of the arch 17 joins the retort, there is provided a longitudinally extending angle iron 21 which is as long as the retort 25 and which extends outward and then has a downwardly extending flange 22, and an angle iron 23 of the same character as the angle iron 21 extends along the retort and is attached thereto or otherwise mounted at the junction of the brickwork base 12 with the retort. The flanges of these angle irons 30 form guides for the reception of a plurality of shield plates 24 which are preferably of heavy metal and which are curved to conform to the curvature of the retort and which, except as hereinafter provided, lie against the wall of the retort so that the wall of the retort where it is exposed to the direct action of the fire is very thick and heavy. 35 This construction permits the ready removal of these shield plates and the replacement thereof. Of course, I have shown a plurality of shield plates within these channel irons or guide irons 21, but it will be understood that these sections may be of any desired size and that the shield might be formed of one section extending the entire length of the retort and removable or replaceable as a whole.

100 In Fig. 4 I show a modification of the construction illustrated in the drawings, wherein 105

110

the retort 10 is formed with upper and lower sections 10^a and 10^b connected by lateral, relatively heavy boiler plate sections 10^c, to which the angle irons 21 and 23 are attached, and which angle irons hold the shield plates 24 in place. It will be understood that in both forms of my invention the shield plates fit loosely in the guides 21 and 23 so that they can be readily removed.

10 It will be noted that one-third of the bottom of this retort is incased in masonry 12. The fire passages 19 are 36" deep and the shield plates have a height greater than 36". The retort is thus protected on its sides and 15 the shield plates can be replaced by simply sliding the old ones out and new ones put in place. This change can be made in five minutes without the removal of any masonry and without the necessity of entirely cooling 20 the retort, thus saving considerable lost time every time that a section of shield plate is replaced. The object of preventing the fire from being directed against the bottom of the retort is to prevent the intense heat 25 coming in direct contact with the lowest portion of the retort wherein the melted tar and heavy oils gather. If heat were directed directly against this portion of the retort, the heat would burn up the most valuable 30 products of the wood distillation, that is the valuable oils which flow along with the tar and are afterward separated by refining the tar. It would, of course, be possible to place the shield plates along the bottom of 35 the retorts and along the sides of the retorts and the fire against the bottom, but in this case the fire would have to be very slow and light in order to keep from burning up the valuable oils. Thus it would take several 40 days to work off a charge of wood. By intensely heating the side of the retort and keeping the bottom cool by the brickwork 12, I provide a retort which will work off a charge of wood in approximately twelve 45 hours without any loss of valuable oils or tar. With these shield plates it takes from about twelve to fourteen months before the retort wall behind the shield plates burns out. Where the shield plates are not used 50 and the furnace is fired directly against the retort at the sides, a charge of wood may be distilled in about 8 hours, but the wall of the retort will be burned out in about two weeks. Shield plates which are made of 55 1½" cast iron plates will last for many months, depending on the thickness of the plates, and then readily replaced with new shield plates without having to replace or patch the retort. In that form of retort 60 shown in Fig. 4, heavy boiler plate is used for the sections 10^c of the retort which permits the retort to last very much longer before the necessity of repairing the retort arises, and then the retort may be readily 65 repaired by the insertion of new sections 10^c.

While I have illustrated a particular form of retort and particularly designed for the purpose of wood distillation, I do not wish to be limited to this, as it is obvious that the retort may be used for other purposes.

70

I claim:—

1. In a retort construction, a base of refractory material, a retort supported upon the base, the middle portion of the retort being protected by the base and the base extending laterally on each side beyond the retort, arches extending upward from the base toward the upper portion of the retort on each side and defining with the base longitudinally extending fire passages, and shield plates of heat conducting material disposed along the opposite sides of the retort and coinciding with said fire passages.

75

2. In a retort construction, a base of refractory material, a retort supported upon the base, the middle portion of the retort being protected by the base and the base extending laterally on each side beyond the retort, arches extending upward from the base toward the upper portion of the retort on each side and defining with the base longitudinally extending fire passages, and shield plates of heat conducting material disposed along the opposite sides of the retort and coinciding with said fire passages, said 80 shield plates being formed in sections removable from one end of the retort structure.

85

3. In a retort construction, a base of refractory material, a retort supported upon the base, the middle portion of the retort being protected by the base and the base extending laterally on each side beyond the retort, arches extending upward from the base toward the upper portion of the retort on each side and defining with the base longitudinally extending fire passages, irons attached to the retort on each side thereof and disposed at the junction of said arches with the retort and at the junction of the base with the retort, and shield plates disposed 90 in said irons and held in place thereby against the opposite walls of the retort.

95

4. In a retort structure, a cylindrical retort proper, a base upon which the retort is mounted, said base covering the bottom of the retort and extending laterally beyond the opposite sides thereof, the top of the retort being covered with protective material, guide irons attached to the retort at the junction of the arch with the retort and at the junction of the base therewith, and heavy, metallic shield plates disposed in said guide irons and removable therefrom and protecting the retort from the direct action of the heat in the fire passages.

100

5. A retort having one portion thereof formed by a relatively heavy, removable section, a guide iron carried by said section, a metallic shield plate supported by said guide irons in contact with said section, and 105

110

115

120

125

130

a furnace and fire passage coincident with said shield plate.

6. In a retort structure, a base of refractory material, a retort supported upon the base, the middle portion of the retort being protected by the base, arches extending upward from the base toward the upper portion of the retort on each side and defining with the base longitudinally extending fire 25 passages, a protective covering extending over the top of the retort and extending downward to the upper portions of the arches, and shield plates of heat conducting material disposed along the opposite sides 30 of the retort and coinciding with said fire passages and extending from the base to the point of intersection of the arches and retort.

7. In a retort structure, a base of refractory material, a retort supported upon the

base, the middle portion of the retort being protected by the base, arches extending upward from the base toward the upper portion of the retort on each side and defining with the base longitudinally extending fire 25 passages, a protective covering extending over the top of the retort and extending downward to the upper portions of the arches, and shield plates of heat conducting material disposed along the opposite sides 30 of the retort and coinciding with said fire passages and extending from the base to the point of intersection of the arches and retort, said shield plates being formed in sections removable from one end of the retort 35 structure.

In testimony whereof I hereunto affix my signature.

E. E. QUINKER.
